UNITED STATES PATENT OFFICE.

GARRETT F. HUGHES, OF CHICAGO, ILLINOIS.

DISPLAY HANGER.

Application filed December 6, 1922. Serial No. 605,150.

To all whom it may concern:

Be it known that I, GARRETT F. HUGHES, a citizen of the United States, residing at Chicago, in the county of Cook and State of Illinois, have invented certain new and useful Improvements in Display Hangers, of which the following is a specification.

This invention relates generally to store furniture, and pertains particularly to a new article of manufacture in the nature of a hanger or fixture whereby articles may be suspended for the purpose of display, dispensing, or service. It has particular application for use as a display hanger for bunches of bananas.

The general object of the invention is the provision of an article of the sort described which will constitute a sightly, convenient, economical and labor-saving utility adapted for use in a variety of locations in a retail store-room or window.

A particular object of the invention is the provision of such a device which will facilitate the slinging or hanging of a bunch of bananas, or other material, in a desired location for display and dispensing, the arrangement being such that it may be operated entirely by one person.

Another particular object is the provision of such a device which is specially adapted to support a suitable sign or display card, and to maintain the same in a desired position, as, for example, with the face of the display card toward a window.

Other and further objects of the invention will be pointed out hereinafter, indicated in the appended claims, or obvious upon an understanding of the present disclosure.

For the purpose of this application I have illustrated in the accompanying drawing forming a part of this specification, one form in which the invention may be embodied, but it is to be understood that the same is submitted for the purpose of illustration only, and that it is not to be accorded the effect of limiting the invention secured by the appended claims, in any fashion, short of its true and most comprehensive scope in the art.

In the drawing,

Fig. 1 is a front elevational view of the device illustrating its use as a supporting device for a bunch of bananas;

Fig. 2 is also an elevational view, but with the sign or display card removed; 55

Fig. 3 is a cross-section, enlarged, substantially on line 3—3 of Fig. 1; and

Fig. 4 is a side elevational view of the device as illustrated in Fig. 2.

It is customary in many retail stores to suspend various articles for the purpose of display and to facilitate their being dispensed to customers, a familiar instance being the practice of hanging a bunch of bananas in a show window or from the ceiling of the 65 store-room. This customarily has been accomplished by simply suspending them at the end of a cord, wire or rod which is suitably secured to a support at its upper end. Such arrangements are usually unsightly 70 and inconvenient, and also unsuitable by virtue of the fact that they permit rotation of the suspended material, rendering it difficult to maintain a desired side thereof in position for inspection, as toward a window, aisle or 75 other location from which it may be easily inspected. The present invention is designed to afford a thoroughly practical specialty, which possesses novel features of utility and construction. 80

The nature of the invention may best be understood by reference to the illustrated embodiment in detail, the various parts thereof being designated by reference characters. It will be understood that the numeral 1 designates a suspension bracket having a looped vertically extending portion in which a pulley 2 is rotatably mounted. The upper end of the suspension bracket is provided with attaching means 4 whereby it 90 may be suspended from a suitable support as by means of the screw eye 5. The suspension bracket is provided with portions affording connections for the mounting of 95 guide tubes 6 thereon. In the form illustrated the bracket 1 is formed of a strip of metal bent into the form of a loop, between the ends of which strip laterally extending clips 7 are secured by screws 8. The extremities of these clips are shaped to embrace the guide tubes 6 adjacent their upper ends, and are clamped thereon by the screws 8 which draw the clips together. The upper ends of the tubes 6 may be provided with 100 collars or shoulder portions 6^a which prevent downward movement of the tubes in the 105

clip. The guide tubes 6 are further maintained in parallel relationship by one or more spacing clips 9 clamped to lower portions of said tubes as by means of the screws 10. Telescopically fitted in the guide tube 6 are extensible tubes 11 which are connected below the lower ends of the guide tubes by a clip 12 which maintains the extensible tubes 11 in proper spaced and parallel relationship for telescopic movement in the guide tubes 6. A suitable flexible suspension member 14, which may be a window cord of proper length, is threaded through the guide tubes 6 and extensible tubes 11 so that its ends project from the lower ends of the latter and its intermediate portion passes over the pulley 2. One end of the flexible extension member is provided with suitable attaching means 15 whereby the material to be supported may be fastened to the suspension member. The length of the flexible suspension member is sufficient to allow the attaching means 15 to be drawn down to a location where it may be connected conveniently to the material to be suspended. The flexible suspension member should slide easily through the tubes and over the pulley so that the suspended material may be drawn up or lowered readily. When the attaching means 15 is drawn up to the end of the extensible tube 11, the other end portion of the flexible suspension means may be wound around it or around the lower portion of the fixture and secured by knotting or in any other convenient fashion.

Upon the spacing clips 9 a suitable sign or display card 16 may be secured by means of the screws 10, suitable spacers 17 being interposed if necessary.

In the employment and operation of the device, it is suspended in the desired location so as to maintain the display card facing in the desired direction. This is accomplished by means of the attaching means 4 and screw eye 5, the relationship of which will tend to maintain the device against rotation. Depending upon the elevation at which it is desired to support the material, the extensible tubes 11 may be adjusted in the tubes 6. The device thus can be accommodated to ceilings or supports of different elevation. The material to be suspended having been brought to a position under the fixture, the attaching device 15 is drawn down and engaged with the material. Then, by drawing upon the other end of the flexible suspension means 14, the material may be hoisted to the desired elevation, and there secured in the manner above mentioned. The entire weight of the suspended material is carried by the flexible suspension means 14 and the bracket 1. The tubes function as guides which prevent the suspension means becoming twisted either incident to the mounting of the material or after it is

suspended. The material may be mounted on the device in this fashion by one person without assistance. The display card 16 may be provided with appropriate advertising matter which, due to the construction of the device, will be maintained in the desired position and in association with the suspended material.

I claim:

1. As an article of manufacture, a display hanger comprising a suspension bracket arranged for attachment to a support, tubes rigidly fixed to said bracket whereby they are maintained in collateral relationship, a flexible suspension member arranged to travel through said tubes and having support on the bracket independently of the tubes, means connecting the tubes below the bracket to maintain them in spaced relationship, said suspension member being arranged for attachment at one end to the supported material.

2. A display hanger comprising, in combination, a suspension bracket arranged, for attachment to a support, guide tubes fixed to said brackets and depending therefrom, extension tubes telescopically movable in the guide tubes, a flexible suspension member arranged to travel through said extension and guide tubes, means on the bracket affording support to the suspension member above the tubes, said suspension member being arranged for connection to supported material.

3. A display hanger comprising, in combination, a suspension bracket, supporting means for maintaining the position of said bracket on the support, a tube supported on said bracket and depending therefrom, a flexible suspension member having support on the bracket and arranged to travel through the tube, said suspension member being arranged for connection at one end to the supported material, a clip mounted on said tube, and a display member mounted on the clip for support on the tube above the supported material.

4. A display hanger comprising, in combination, a suspension bracket arranged for attachment to a support, guide tubes fixed to said bracket and depending therefrom in collateral relationship, means engaging said tubes below the bracket to maintain them in spaced relationship, a rotary member mounted on the bracket, a flexible suspension member supported on the rotary member and arranged to travel through the tubes, said suspension member including means at one end for connection to supported material.

5. A display hanger comprising an attaching member, a suspension bracket depending therefrom, a pulley mounted on said bracket, guide tubes mounted on the bracket and depending therefrom in collateral relationship,

extension tubes telescopically movable in said guide tubes, and a flexible suspension member running through the extension and guide tubes and over the pulley and having its ends free at the lower extremities of the extension tubes.

In testimony whereof I have hereunto

subscribed my name in the presence of two subscribing witnesses.

GARRETT F. HUGHES.
